CIGARETTE VENDING MACHINE CABINET

Mahlon W. Kenney, 1010 Forest Ave., Oak Park, Ill.,
and Carl W. Sundberg, 360 Martell Drive, Bloomfield Hills, Mich.

Filed Aug. 17, 1959, Ser. No. 57,201

Term of patent 14 years

(Cl. D52—3)

Fig. 1 is a reduced front perspective view of a cigarette vending machine cabinet showing our new design;

Fig. 2 is a front elevational view thereof;

Fig. 3 is a left side elevational view thereof, the right side elevational view being substantially a mirror image thereof; and

Fig. 4 is a top plan view thereof.

The rear of the vending machine is plain in appearance.

We claim:

The ornamental design for a cigarette vending machine cabinet, as shown and described.
